UNITED STATES PATENT OFFICE

135,761

DESIGN FOR A COMBINED FISHING ROD HANDLE AND REEL

Thomas C. Fanshier, Oklahoma City, Okla.

Application June 8, 1942, Serial No. 107,157

Term of patent 14 years

To all whom it may concern:

Be it known that I, Thomas C. Fanshier, a citizen of the United States, residing at Oklahoma City, in the county of Oklahoma and State of Oklahoma, have invented a new, original, and ornamental Design for a Combined Fishing Rod Handle and Reel, of which the following is a specification, reference being had to the accompanying drawing, forming part thereof.

Figure 1 is a top plan view of a combined fishing rod handle and reel, showing my new design.

Figure 2 is a side view thereof; and
Figure 3 is a bottom plan view.

I claim:

The ornamental design for a combined fishing rod handle and reel, as shown.

THOMAS C. FANSHIER.
